UNITED STATES PATENT OFFICE.

ELMER B. STONE, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

SAFETY DEVICE FOR POWER-OPERATED MACHINES.

1,111,042.

Specification of Letters Patent. Patented Sept. 22, 1914.

Application filed April 30, 1913. Serial No. 764,592.

To all whom it may concern:

Be it known that I, ELMER B. STONE, a citizen of the United States, and a resident of New Britain, in the county of Hartford and State of Connecticut, have invented a new and Improved Safety Device for Power-Operated Machines, of which the following is a specification.

My invention relates to the class of devices employed to prevent the operation of machines while the person of the operative is in dangerous positions, and an object of my invention, among others, is to provide a device of this class that while effectually performing the functions required of it shall be so sensitive to the movements of the operator as to present substantially no obstacle to the movements of the hands or arms in the operation of the machine.

One form of device embodying my invention, and in the construction and use of which the object herein above set out, as well as others, may be attained, is illustrated in the accompanying drawings, in which—

Figure 1 is a side view of a drop press showing my improved safety device attached thereon, and illustrating its manner of operation. Fig. 2 is a view in front elevation of the press showing my improved safety device in place thereon. Fig. 3 is a detail diagrammatic view showing the device in a different position from that of the other figures and illustrating a different means of support. Fig. 4 is a like view showing the apparatus in still another position and also showing a still different means for supporting the device.

While my apparatus is not limited in its use to any specific kind of machine, yet as it is especially applicable for use in connection with power presses and like structures I have selected such a machine for the purpose of illustrating my invention herein. In such drawing the numeral 5 indicates legs, 6 the frame, 7 the driving shaft, 8 the driving pulley, 9 the plunger, 10 the die or work performing member, and 11 the bed of a power press, all of which parts may be of ordinary and well known construction and which include a clutch member operated by a clutch or starting lever 12 to connect the pulley 8 with the shaft 7 to rotate the latter in any common and well known manner. In the form of device herein shown this clutch

lever is pivotally mounted in a bracket 13 secured to the side of the frame, said lever having a foot 14 connected by a rod 15 with a pedal 16 pivotally mounted in convenient position for access by the foot of the operator.

My invention contemplates a structure that shall present little, if any, inconvenience to the operative performing the operations required, the device being so made that the hands of the operative are free and unobstructed. In effecting such a result I provide a dog 17 that shall be placed in the path of movement of the foot 14 of the lever 12 whenever the hands of the operative are in dangerous positions and liable to injury by the movement of the plunger 9. In the form of mechanism herein shown this dog constitutes the end of a sliding bar 18 mounted, as to its end, to slide in a dog support 19 secured to the side of the machine frame, the other end being pivotally attached to a dog operating arm 20 secured to a dog operating shaft 21 mounted in a supporting frame removably attached to the machine frame. In order that this supporting frame may be adapted to various conditions a bracket 22 having a supporting clamp socket 23 is rigidly fixed on the machine frame, and a frame support 24 is adjustably secured in this socket, this construction enabling the support to be rotatably or longitudinally adjusted. The end of this support is preferably flattened and is received in a slot in a cross bar 25 of a supporting frame that also includes two end bars 26 in which the dog operating shaft 21 is rotatably supported.

A dog operating bar or safety member 27 is mounted upon the shaft 21 so that it may move freely toward and from it but at the same time so that any other movement of the bar will impart rotary movement to said shaft. To this end the bar 27 is suspended from the dog operating shaft by slotted arms 29 within the slots in which the shaft is received, and one of said arms also receives a crank 28 formed at one end of the shaft.

The bar 27 is preferably constructed of bamboo or other light material, and is adapted to rest against or be located immediately in front of or over the arms of the operative, and it will be seen that this mounting of the bar or safety member and its construction will cause it to readily re-

spond to the movements of the operator's arms in various directions with substantially no obstruction to such movement. The mounting of the frame is such that the bar may be readily adjusted to suit different or varying conditions and to place it in such positions as to cause its operation, whenever the hands of the operator are placed in dangerous positions with respect 5 to the dies, to move the dog 17 into the path of movement of the foot 14 of the lever 12, and it will thus be impossible, whenever the operator's hands are in such dangerous positions, to operate the clutch parts to start the 10 running of the machine. The construction and adoption of the device is such that it is always in position to serve the purpose for which it is intended, requiring no act on the part of the operative to place it in readiness 15 to serve such purpose.

An important feature of my invention resides in the bar or safety member necessarily actuated by the person of the operator in manipulating the work, the term "person" 20 as employed herein having its regular meaning, denoting the body or any member thereof, as the arms, legs, hands, feet, or the like.

A distinctive feature of my invention resides in the safety device that is an active 25 agent and that is arranged to be directly moved by the operator before the treadle, clutch rod &c., for manually controlling the operations of the machine, can be operated. In other words, the safety device is initially 30 or primarily moved for the purpose of releasing the treadle to permit its operation.

The mechanism herein illustrated and described for carrying out my idea is only one of the several forms contemplated by 35 me to effect this result, and I do not therefore limit my invention to the exact construction herein set forth.

I claim—

1. In combination with the work performing member of a machine, manually actuated means for controlling the operations of said member, a support, a safety member movably mounted on the support and located in position to be necessarily engaged and moved by the person of the operator in manipulating the work, and means connected with said safety member to control the operation of said manually actuated controlling means.

2. In combination with the driving member of a machine, manually actuated means for controlling the operations of said member, a support, a safety member movably mounted on the support in position to be necessarily engaged and moved by the person of the operator in manipulating the work, and means connected with said safety member to control the operation of said manually actuated controlling means.

3. In combination with the work performing member of a machine, manually actuated means for controlling the operations of said member, a support, a safety member movably mounted on the support in position to be necessarily engaged and moved by the person of the operator in manipulating the work, and means connected with said safety member to control the operation of said manually actuated controlling means.

ing member of a machine, manually actuated means for controlling the operations of said member, a lock to prevent operation of said manually actuated means, a support, a safety member movably mounted on the support in position to be necessarily engaged by the person of the operator in manipulating the work, and a connection between said safety member and said lock to operate the latter.

4. In combination with the work performing member of a machine and the means for operating said member, means for preventing its operation, a support, a safety member mounted upon the support in position to be necessarily engaged and moved by the person of the operator in manipulating the work, and means connected with said safety member and operated thereby to control the operation of the means for preventing operation of said member.

5. In combination with the work performing member of a machine, means for driving said member, means for connecting said driving means with and for disconnecting it from said work performing member, manually actuated means for controlling the operations of said connecting and disconnecting means, a lock for said controlling means, and means connected with said lock to operate it and located in position to be necessarily engaged by the person of the operator in the regular operation of manipulating the work.

6. In a safety device, in combination with the work performing member of a machine, manually actuated means for controlling the operations of said member, a safety member movably supported by the frame of the machine in position to be necessarily engaged and moved by the person of the operator in manipulating the work, and means connected with said safety member to control the operation of said manually actuated controlling means.

7. In combination with the work performing member of a machine, manually actuated means for controlling the operations of said member, a lock to prevent the operation of said manually actuated controlling means, a support, and a safety member mounted to swing freely on said support in position to be necessarily engaged by the person of the operator in manipulating the work, said safety member being connected to said lock to operate it.

8. In combination with the work performing member of a machine, a driving member therefor, means connecting said driving member with and for disconnecting it from said work performing member, a support, a safety member movably mounted on the support in position to be necessarily engaged and moved by the person of the operator in manipulating the work, and means connected with said safety member to control the operation of said manually actuated controlling means.

connecting said safety member with said connecting and disconnecting means.

9. In combination with the work performing member of a machine, means for intermittently driving said member, a support, a safety member movably mounted on the support in position to be necessarily engaged and moved by the person of the operator in manipulating the work, and connections between said intermittent driving means and said safety member to control the operations of the former by the latter.

10. In combination with the work performing member of a machine, manually actuated means for controlling the operations of said member, a lock to prevent operation of said manually actuated controlling means, a support, a rock shaft mounted on the support, a safety device suspended from said rock shaft in position to be necessarily engaged by the person of the operator in manipulating the work, and a connection between said safety member and lock for operation of the latter.

11. In combination with the work performing member of a machine, means for intermittently driving said member, means for controlling the operations of the latter, a support, a safety member mounted on said support in position to be necessarily engaged and moved by the person of the operator in manipulating the work, and an actuating connection between said safety member and the means for controlling the operations of said intermittent driving means.

12. In a safety device, in combination with means for intermittently driving a machine, means to control the operations of said intermittent driving means, a safety device supported in position to be necessarily engaged and moved by the person of the operator in manipulating the work, and operative connections between said safety

device and the means for intermittently controlling the operations of said driving means.

13. A safety device including a member to prevent operation of a machine, controlling means located in position to be necessarily engaged by the person of the operator in manipulating the work, and a connection between said controlling means and the member for preventing operation of the machine to cause operation of the former by the latter.

14. In combination with the work performing member of a machine and the means for operating said member, means for preventing its operation, controlling means supported in position to be necessarily engaged and moved by the person of the operator in manipulating the work, and operative connections between said controlling means and the means for preventing operations of said member.

15. In combination with the work performing member of a machine and the means for operating it, a safety member located in position to be necessarily engaged by the person of the operator in manipulating the work, and connections between said safety member and said operating means for control of the latter by the former.

16. In combination with the work performing member of a machine, manually operated means for controlling operations of said member, a safety member supported independently and normally adapted to engage the person of the operator and be moved thereby in feeding blanks to the machine, and means to cause the safety member to control the action of said manually operated controlling means.
